FREEZER

Original Filed Nov. 12, 1926

V. W. Klein,

INVENTOR

BY Victor J. Evans

ATTORNEY

P. J. Hickey.

WITNESS:

UNITED STATES PATENT OFFICE.

VICTOR W. KLEIN, OF LAKE CHARLES, LOUISIANA.

FREEZER.

Application filed November 12, 1926, Serial No. 148,045. Renewed September 10, 1928.

This invention relates to improvements in freezers especially adapted for use in freezing ice cream and ices and contemplates a provision of reciprocating paddles or dashers 5 and a scraping mechanism carried by the freezer whereby all of the mixture sticking to the sides and bottom thereof will be readily and easily removed and in so doing the mixture will be thrown upon the paddles or dashers to thoroughly mix and freeze the same.

Another object of the invention comprehends an operating means for the scraping means as well as the paddles or dashers to 15 provide an operating means which when geared up and due to the eccentric interfitting relation of the various parts it will be noted that both rotary and reciprocatory movement will be imparted to the freezing 20 apparatus.

With the above and other objects in view, the invention further includes the following novel features and details of construction, to be hereinafter more fully described, illustrated in the accompanying drawings and pointed out in the appended claims.

In the drawings:

Figure 1 is an elevation of the invention.

Figure 2 is a longitudinal section taken on line 2—2 of Figure 1.

Figure 3 is a transverse section taken through a portion of the freezing apparatus.

Figure 4 is a similar view taken through the bottom of the freezer and showing the 35 relative positions of the scraping apparatus.

Referring to the drawing in detail, wherein like characters of reference denote corresponding parts, the reference character 10 indicates a bucket, and 11 the ice cream freezer, 40 the latter being packed within the bucket 10 in the usual and ordinary manner or mechanically refrigerated. A removable closure cap or cover 12 includes a centrally disposed opening having an upstanding annular flange 13 surrounding the marginal edges thereof to receive a housing 14. The bucket 10 also includes a cover 15 having an opening 16 receiving the upper end of the housing 14. An annular flange member 17 carried by the 50 cover 15 receives for rotation therein the housing 14.

Fixed or otherwise secured to the housing 14 is a beveled gear 18 seated upon the periphery of the flanged member 17. A substantially U-shaped bracket 19 has its ends carried upon the cover 12 of the freezer 11 and disposed an appreciable distance above the beveled gear 18. A pair of driven shafts 20 journaled within the sides of the bracket 19 have a beveled gear 21 carried upon the lowermost shaft and meshed with the beveled gear 18 which is rotated through meshing engagement of a gear 22 correspondingly associated with a small gear 23 carried upon the upper shaft. The upper driven shaft has included 55 upon one end thereof a relatively large gear wheel 24 which is meshed with a driving gear 25 included upon the upper end of a motor shaft from a motor 26 carried by the bracket 19. Said motor is held against displacement 60 through the instrumentality of bands 17 carried by the bracket. It will thus be noted upon starting the motor 26 that the gears as mentioned will be caused to rotate. The housing 14 will also rotate within the flange 75 members 13 and 17 and in order that the operation of the housing 14 may be reduced to practical use I provide a cross arm 28 upon the lower end thereof within the freezer 11 and which has pivotally mounted within the 80 ends thereof and the corresponding portions of an additional cross arm 28 the ends of scrapers 29 disposed adjacent the innerside walls of the freezer 11. Said scrapers will be caused to scrape the innerside walls of the 85 freezer upon successive revolutions of the housing due to the agency of centrifugal force whereby the mixture sticking to the innerside walls of the freezer will be thrown inwardly toward the center thereof to mix the 90 same with the major portion of the mixture. The lower cross arm 29 includes a pivotally mounted scraper fan 31 which is helically pitched as illustrated in Figure 1 to scrape 95 all of the mixture which has settled within the bottom of the freezer.

As mentioned in the foregoing I provide means for reciprocating a plurality of paddles or dashers within the freezer 11 and in so doing I provide a separable eccentric housing 32 which receives for rotation within a groove 33 an eccentric or cam 34 fixed upon

the uppermost of the driven shafts 20. The housing 32 includes a longitudinally disposed elongated slot 35 receiving the lowermost of the shafts 20 to provide sufficient space to 5 clear the shaft when the housing 32 is reciprocated through the movement of the eccentric or cam 34.

Fixed to the lower portion of the housing 32 and extended through the housing 14 and 10 adapted for reciprocation therein, is a dasher rod 36 which is also disposed an appreciable distance within the freezer 11.

Fixed to and arranged at spaced intervals upon the dasher rod 36 is a plurality of 15 paddles or dashers 37 which will reciprocate within the freezer 11 upon successive reciprocations of the dasher rod 36. It will thus be noted that a novel form of operating means is provided for this especial type of freezing 20 apparatus, using one agency of power, will impart rotary movement to the scraper 29 within the freezer 11 and also a reciprocating movement to the dasher rod 36 and paddles or dashers 39 carried thereon.

25 In order to provide means for whipping air in the making of frozen dainties having smoothness of textures, I provide a compressed air pump 38 mounted upon the cover 15 of the bucket 10, and having its plunger 30 rod 39 connected with the lower end of a pivoted link 40. Said link is connected at its opposite end to an eccentrically mounted trunnion 41 upon the outer sides of a pulley wheel carried upon the outer free end of the 35 upper driven shaft 20. The latter upon successive revolutions will reciprocate the plunger rod 39 within a pump 38 to expel compressed air through a pipe 42 coiled within the bucket 10 and encircling the freezer 40. 11. The upper end of the tube 42 is connected to a flexible tube 43 communicating with the upper free end of the dasher 36 whereby the air will be emitted from the lower end of the dasher rod within the freezer 45 11 to whip the mixture to insure smoothness of texture.

A housing 44 is placed upon the cover 15 to enclose the gears 18 and 21 so that the tube 43 will not be injured upon the reciprocation of the dasher rod 36 and operating means therefor.

Manifestly the mechanism may by the construction thereof be readily placed within a receptacle and disposed centrally of the 55 vertical axis thereof.

The invention is susceptible of various changes in its form, proportions and minor details of construction, and the right is herein reserved to make such changes as properly 60 fall within the scope of the appended claims.

Having thus described my invention, what is claimed is:

1. An ice cream freezer comprising a receptacle, a freezer carried thereby, closure

caps for the receptacle and freezer, a housing 65 extended through said caps, a bevel gear fixed to the upper end of the housing, cross bars disposed within the freezer and connected with the housing, a scraper fan carried by one of the cross bars, scraper members journaled between the ends of the bars 70 adjacent the inner side walls of the freezer, a dasher rod extended through the housing and within the freezer an appreciable distance, a plurality of dashers carried by the 75 dasher rod at spaced intervals thereon, a substantially inverted U-shaped supporting member carried upon the receptacle closure cap, a motor supported upon the upper end of the supporting member, a pair of geared 80 driven shafts journaled within the sides of the supporting member and connected with the motor, a cam fixed upon one of the shafts, gearing means included upon the other driven shaft and meshing with the beveled 85 gear, and an eccentric housing encircling the cam and connected with the upper end of the dasher rod.

2. An ice cream freezer comprising a receptacle, a freezer arranged within the receptacle, closure caps for the receptacle and freezer respectively, a housing extending through the caps, a beveled gear fixed to the upper end of the housing, a cross bar carried upon one end of the housing within the 90 freezer, an auxiliary cross bar having a helically pitched fan scraper upon the lower side thereof adjacent the bottom of the freezer, scraper members vertically disposed within the 95 freezer having their respective ends thereof journaled between the extremities of the cross bars, a supporting member carried by the receptacle closure cap and supporting a motor thereon, upper and lower geared 100 driven shafts having their ends journaled within the opposed sides of the supporting member and connected with the motor, a beveled gear carried by the lower shaft and meshing with the first mentioned beveled gear, an eccentric fixed to the upper shaft, 105 and a separable eccentric having its lower end fixed to the upper end of the dasher rod and receiving the lower driven shaft within an elongated slotted portion.

3. An ice cream freezer comprising a receptacle, a freezer arranged within the receptacle, closure caps for the receptacle and freezer respectively, a housing extending through the caps, a beveled gear fixed to the upper end of the housing, a cross bar carried upon one end of the housing within the 110 freezer, an auxiliary cross bar having a helically pitched fan scraper upon the lower side thereof adjacent the bottom of the freezer, scraper members vertically disposed within the 115 freezer, having their respective ends journaled between the extremities of the cross bars, a supporting member carried by the 120

receptacle closure cap and supporting a motor thereon, upper and lower geared driven shafts having their ends journaled within the opposed sides of the supporting member and connected with the motor, a beveled gear carried by the lower shaft and meshing with the first mentioned beveled gear, an eccentric fixed to the upper shaft, and a separable eccentric carried by the dasher rod being adapted to receive the first mentioned eccentric to derive the necessary momentum for the dasher rod.

In testimony whereof I affix my signature.

VICTOR W. KLEIN.
